US0D1041007S

(12) United States Design Patent (10) Patent No.: US D1,041,007 S
(45) Date of Patent:  Sep. 3, 2024

(54) NASAL MUCUS EXTRACTOR

(71) Applicant: Kody Thomas Zaumseil, Half Moon Bay, CA (US)

(72) Inventor: Kody Thomas Zaumseil, Half Moon Bay, CA (US)

() Term: 15 Years

(21) Appl. No.: 29/932,165

(22) Filed: Mar. 12, 2024

(51) LOC (14) Cl. 24-02

(52) U.S. Cl.

USPC D24/147

(58) Field of Classification Search

USPC D7/654; D24/119, 133, 146, 147, 151; D28/10, 65, 99

CPC . A61B 2017/246; A61B 17/24; A61F 13/126; A61F 13/38

(57) CLAIM

The ornamental design for a nasal mucus extractor, as shown and described.

DESCRIPTION

FIG. 1 is a top front perspective view of a nasal mucus extractor, showing my new design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

1 Claim, 4 Drawing Sheets
